FOLDING BED COUCH.

APPLICATION FILED NOV. 14, 1908. RENEWED APR. 28, 1910.

977,529.

Patented Dec. 6, 1910.

UNITED STATES PATENT OFFICE.

EDGAR B. MILLERT, OF NEW YORK, N. Y.

FOLDING BED-COUCH.

977,529.

Specification of Letters Patent. Patented Dec. 6, 1910.

Application filed November 14, 1908. Serial No. 432,623. Renewed April 28, 1910. Serial No. 558,237.

To all whom it may concern:

Be it known that I, EDGAR B. MILLERT, a citizen of the United States, and a resident of New York, county and State of New York, have invented certain new and useful Improvements in Folding Bed-Couches, of which the following is a full, clear, and exact description.

This invention relates more particularly to a folding bed couch in which two relatively movable members may be made to fold in a compact space or to be moved so as to make the bed substantially double its width while in an extended position.

The primary object of the invention is to provide a simple and efficient article of the class described in which the entire frame work of the bed may be made of metal and so constructed that it will be light and strong, and the parts readily assembled, and in which the mattress and spring may be made to fold under the upper surface thereof in such a way that it may be made to serve as a shelf and to make the bed very compact, thus overcoming many of the objections incident to the ordinary form of bed in which the parts are made very heavy and cumbersome and are not adapted to be folded in a compact space and serve the double purpose of a bed and couch.

A further object of the invention is to provide a simple and efficient frame for the bed in which one member remains normally stationary and the other member is movable with relation thereto, and carries the mattress and spring, and has certain parts thereof formed with a telescopic connection with the normally stationary member, and to provide an article in which the parts are so supported that the members may be moved relatively with respect to each other without difficulty.

A still further object of the invention is to provide a simple and efficient guard for preventing the members while being folded from coming into contact with the wall and to so support the mattress that it will properly yield to afford the desired comfort while in use.

With these and other objects in view, the invention will be hereinafter more particularly described with reference to the accompanying drawings, which form a part of this specification, and will then be pointed out in the claims at the end of the description.

In the drawings, Figure 1 is a plan view of one form of device embodying my invention showing the same in a folded position. Fig. 2 is an end elevation of Fig. 1. Fig. 3 is a longitudinal section showing the article in position for use as a bed. Fig. 4 is an enlarged vertical section through a part of the frame of one of the members showing how the mattress and spring may be supported to be folded or extended. Fig. 5 is a fragmentary sectional plan, partly in elevation, of one end of the frame extended. Fig. 6 is an enlarged transverse section, taken on a line VI—VI of Figs. 3 and 4. Fig. 6^a is a fragmentary section showing one end of the movable bar connected to the extension member; and Fig. 7 is a fragmentary sectional view, partly in elevation, showing a different form of means for moving the chains to which the mattress spring is connected.

While I have shown and shall refer particularly to a bed couch which may be extended to adapt the same as a single or a double bed, and while the frame is constructed almost entirely of tubular or round metal, it will be understood that the form of the parts of the frame as well as its construction may be changed, and that any of the parts may be formed of other material than metal.

The normally stationary member 10 is provided with upright posts 11 at the front thereof which are connected by the tubular parts or member 12, such as pipe so as to form the front of said member, and at the rear thereof are the uprights or posts 13 which have one part, as 14, offset from the part 15 by a substantially horizontal portion 16. These uprights or posts 13 are connected at their upper and lower ends by the bars or parts 17, and the front and rear posts 11 and 13 may be connected by the tubular bars or parts 18 and these tubular parts may be held to each other by means of couplings, ells, or other fittings such as are employed in pipe fitting and architectural work so that the parts may be cheaply and easily made and assembled and still be comparatively light and very strong. These posts 11 and 13 may have suitable casters at their lower ends and these casters may be formed by holding a ball 19 in a clamping member 20 secured to the lower end of the posts.

To support the mattress and spring so that the same may be extended or folded, I

secure to the member 10 at or near each end thereof a substantially U-shaped support or device 21. These devices 21 are each tubular and are held to the posts 11 and 13 by brackets or otherwise, and slidably held in the part or leg 22 of each device 21 is a bar or part 23 of the relatively movable or extension member 24. Each bar or part 23 is adapted to slide in the part 22 of the U-shaped devices so as to form a telescopic connection therewith, and held to the bars or parts 23 at the outer ends thereof are the posts or uprights 25 forming the legs for said member 24. These legs or posts may be provided with casters 26 similar to those shown on the posts 11 and 13, and said posts 25 are connected by longitudinally-extending bars or parts 27 to secure the necessary strength, the said bars and posts being connected by the usual form of T-shaped fittings. The bars 23 are each connected at one end to a chain 28 which is movably held within one of the devices 21, and each chain is provided with a plurality of pins or bolts 29 which project outwardly through a slot 30 on the inner side of each of the U-shaped members 21. These slots 30 conform to the shape of the devices 21, and extend the greater part of the length of the lower legs 31 or stems of said devices 21 so that the chains 28 may be moved along the lower legs when the bed is in a folded position. The inner end of each chain is fastened to a flexible connection 32, as a wire, cord or the like, and the other end of said flexible connection passes around a sheave or pulley journaled on the upper part of the stem 31 of each member 21 and is held to a longitudinally-extending bar or rod 33, the ends 40 of which project within the slots 30 and are fastened to the inner end of the bars or parts 23 of the extension member 24 so that when the extension member 24 is forced inward, the chains or devices 28 will be positively moved therewith within the devices 21 and will likewise move in the opposite direction when the member 24 is in an extended position.

Each bolt 29 may be provided with a roller 34 which may be smooth or flanged as desired, and these rollers are adapted to move along the lower edge, as 35, of the slots 30 so as to properly guide and support the chain or other connection within the tubular devices 21, and the parts 23 of the extension member 24 may be also provided with bolts 36, on which may be arranged rollers 37 or not as desired, which are adapted to move along the edge 35 forming a guide therefor when said extension member is moved outward or inward. The bolts 29 and 36 are each provided with an eye 38 to which may be fastened one end of a spring 39, the other end of which is held to a suitable mattress-supporting member 40, which

serves to support the mattress and which may be held thereto in any desired way.

As will be seen when the extension member is folded, the mattress and mattress spring will be positively moved so as to fold inward along the lower leg or stem 31 of the U-shaped devices so as to be entirely out of the way and will be likewise moved in the opposite direction when the member 24 is in an extended position as shown in Fig. 75 3, and when the mattress and spring is folded it will provide a space in which may be packed pillows or other articles.

A shield or guard 41 may extend lengthwise of the bed at the rear thereof, and this shield or guard may be pivoted at 42 to the rear posts or uprights 13 and may be normally forced inward by springs 43 which are fastened to the guard and to the U-shaped devices 21 or other parts of the normally stationary member 10. This guard serves to prevent the mattress from striking the wall when the same is being folded or unfolded, and the offset of the legs or posts 13 serve to compensate for the thickness of 90 the mattress and supporting parts.

Fig. 7 shows how the flexible connection to the chain for moving it along the lower stem or part of the U-shaped devices 21 may be dispensed with. The chain 44 is held to the extension member 24, and said chain is engaged by a sprocket wheel 45, one for each chain, which may be connected by a shaft 46. The teeth of the sprocket wheel 45 engage the chain 44, both above and below so that as the chain is moved inward the lower teeth will move the chain through the lower leg or stem 31 of the U-shaped devices, the said chain being supported by rollers as in the other figures if desired.

From the foregoing it will be seen that a simple and effective bed couch is provided in which two members are arranged to be moved relatively with respect to each other to permit the bed to be extended or folded in a compact space; that simple means is provided whereby the spring and mattress may be automatically folded downward, and inward out of the way; that the bed may be made entirely or partly of metal and the tubular parts joined together in such a way that it may be easily assembled and will be very strong and comparatively light in construction; that said bed may be made ornamental in appearance, and that one of the members may have a part thereof in telescopic connection with the other member.

Having thus described my invention, I claim as new and desire to secure by Letters Patent:—

1. An article of the character described, comprising a normally stationary member having a plurality of rear and a plurality of front supporting legs properly braced, a substantially U-shaped member held adja-

cent to each end of said member, said U-shaped part or member being open at one end, and an extension member having a part thereof adapted to fit and slide in a part of 5 the U-shaped member.

2. An article of the character described, comprising a normally stationary member having rear and front supporting legs properly braced, a substantially U-shaped member held adjacent to each end of said member, said U-shaped part or member being open at one end, and an extension member having a part thereof adapted to fit and slide inward along the lower leg or stem of 10 said U-shaped members, substantially as and for the purpose described.

3. An article of the character described, comprising a normally stationary member having a plurality of front and a plurality 20 of rear supporting legs, a device held adjacent to each end of said member, said device being open at one end, and an extension member having a part thereof adapted to fit and slide in a part of said device.

25 4. An article of the character described, comprising a normally stationary member having a plurality of rear and a plurality of front supporting legs properly braced, a substantially U-shaped device held adjacent 30 to the ends of said member, and an extension member having a sliding connection with said device.

5. An article of the character described, comprising a normally stationary member 35 having substantially U-shaped devices supported in a horizontal position adjacent to the ends of said member, said U-shaped devices being slotted on the inner side thereof, a chain adapted to move within the U-shaped 40 part, means carried by the chain for supporting a mattress, and an extension member slidably held to the other member and connected to the chain.

6. An article of the character described, 45 comprising a normally stationary frame having substantially U-shaped devices supported adjacent to the ends of said member, a chain adapted to move within the U-shaped part, means carried by the chain for supporting a mattress, and an extension member 50 connected to the chain and having a part thereof adapted to fit and slide inward along the lower leg or stem of the U-shaped devices, substantially as and for the purpose described.

55 7. An article of the character described, comprising a normally stationary frame having substantially U-shaped devices supported adjacent to the ends of said member, 60 and movable mattress-supporting means supported by said devices and adapted to slide inward along the lower leg or stem of said U-shaped devices, substantially as and for the purpose described.

8. In a bed couch, the combination with a 65 member having a tubular U-shaped device adjacent to each of its ends, said part or device being slotted on one side thereof, of a chain movable in each of said U-shaped devices, means carried by the chain projecting 70 outwardly through the slot and having rollers thereon to guide the chain, mattress-supporting means held to the means projecting from the chain, an extension member also provided with means for supporting a mattress 75 and connected to the chain, and means movable with the extension member for positively forcing the chain in either direction.

9. In a bed couch, the combination with a 80 member having a tubular U-shaped device adjacent to each of its ends, of a chain movable in each of said U-shaped devices, means carried by the chain and projecting outwardly therefrom, mattress-supporting 85 means held to the means projecting from the chain, an extension member also provided with means for supporting a mattress and connected to the chain, and flexible connections movable with the extension member for positively forcing the chains in either direction.

10. In a bed couch, the combination with a 90 member having a U-shaped device adjacent to each of its ends, flexible means movable along said U-shaped devices, mattress-supporting means held to the flexible means, an extension member also provided with means for supporting a mattress and connected to the flexible means.

11. In a bed couch, the combination with 100 a metallic frame forming one member, of U-shaped devices supported near the ends of said frame in a horizontal position, a chain movable in each of the U-shaped devices, a flexible connection attached at one end to the 105 chain, a transversely movable bar extending longitudinally of the frame to which the other end of the flexible connection is attached, an extensible member having parts fitting into a part of the U-shaped devices 110 and connected to the chain and to the longitudinal bar, said U-shaped devices being slotted lengthwise thereof, bolts projecting from the chain and from the extensible member, rollers held to the bolts, a mattress member, springs connecting the mattress with the bolts, and means for slidably holding the frame and extensible member together.

12. In a bed couch, the combination with 115 a metallic frame forming one member, of U-shaped devices supported near each of the ends of said frame in a horizontal position, a chain movable in the U-shaped devices, a flexible connection attached at one end of the chain, a transversely movable bar extending longitudinally of the frame to which the other end of the flexible connection is attached, an extensible member having parts

fitting into a part of the U-shaped devices and connected to the chain and to the longitudinal bar, and means movable with the extensible member and the chains for supporting a mattress.

13. In a bed couch, the combination with a frame forming one member, of U-shaped devices supported near each of the ends of said frame, a chain movable in each of the 10 U-shaped devices, an extensible member, bolts projecting from the chains and from the extensible member, rollers held to the bolts, a mattress member, springs connecting the mattress member with the bolts, and 15 means for slidably holding the frame and extensible member together.

14. In a bed couch, the combination with a metallic frame forming one member, of U-shaped devices supported near the ends of 20 said frame in a horizontal position, a chain movable in each of the U-shaped devices, a flexible connection attached at one end to the chain, a transversely movable bar extending longitudinally of the frame to which the 25 other end of the flexible connection is attached, an extensible member, bolts projecting from the chain and from the extensible

member, rollers held to the bolts, and mattress-supporting means held to the bolts.

15. The combination with a metallic frame, 30 of U-shaped devices located near the ends thereof, an extension member, means movable with the extension member for supporting a mattress, a guard pivotally held to the frame of one of the member and serving to 35 prevent the mattress from touching the wall while the couch is in a folded or extended position, and springs normally holding the guard in an upright position.

16. The combination with a metallic frame, 40 of U-shaped devices located near the ends thereof, an extension member, means movable with the extension member for supporting a mattress, and a guard pivotally held to the frame of one of the members and 45 serving to prevent the mattress from touching the wall while the couch is in a folded or extended position.

This specification signed and witnessed this 11th day of November A. D. 1908.
